UNITED STATES PATENT OFFICE.

JOHN GEORGE TORR, OF SYDNEY, NEW SOUTH WALES, AUSTRALIA.

SPARK-ARRESTER.

1,199,720.

Specification of Letters Patent. Patented Sept. 26, 1916.

Application filed May 12, 1916. Serial No. 97,170.

To all whom it may concern:

Be it known that I, JOHN GEORGE TORR, a subject of the King of Great Britain, residing at Sydney, in the State of New 5 South Wales, Commonwealth of Australia, have invented certain new and useful Improvements in Spark-Arresters, of which the following is a specification.

This invention relates to improvements 10 in spark arresters, for locomotives or stationary engines or furnaces, of the type consisting of a cylindrical or other shaped screen or grid fixedly supported on or over the mouth of the smoke stack. It has been 15 found that spark arresters of this type frequently become clogged owing to the soot particles adhering to the wires or rods forming the screen consequently reducing the draft.

20 The object of the present invention is to remove the adhering soot particles when necessary by operating a lever or handle from the cab of the engine or other convenient position.

25 According to the invention I provide a wire or light metal frame preferably external and concentric with the arrester screen. This frame consists of a number of wires, rods or bars pivoted above the 30 spark arrester and secured to a movable member below it. On the frame are fastened a series of scrapers preferably annular or U-shaped each of which takes against a wire or rod of the screen so that on the 35 frame being moved or reciprocated over a segment of the screen the scrapers remove the soot adhering to the wires thereof. The frame is reciprocated by a rack and pinion or other actuating mechanism operated by 40 a lever or handle.

In the accompanying drawings is illustrated a spark arrester fitted with my improvements, Figure 1 being a sectional elevation. Fig. 2 a plan, and, Fig. 3 an enlarged detail in perspective.

5 represents the wires or rods of a spark arrester screen supported on a fixed frame 6. Pivoted on a central pin 7 is an outer frame consisting of bars 8 corresponding in

number to the rods forming the segments of 50 the frame 6. The bars 8 end in the movable plate 9 and have secured thereon the U-shaped scrapers 10 one for each of the wires 5 in each segment. The pinion 12 on the movable frame is in gear with the segmental rack 13 on the fixed screen frame. On said pinion being rotated the movable frame is carried around and as the openings of the scrapers 10 are slightly greater than the diameter of the wires 5, reciprocation or 60 movement of the outer frame through a segment of the arrester removes any soot adhering to the wires thereof.

Having thus described my invention what I claim as new and desire to protect by Letters Patent is:—

1. A spark arrester comprising a screen formed of a plurality of wires, a rotatable frame, and a series of soot-scrapers carried by the frame, each embracing a wire of the 70 screen.

2. A spark arrester comprising a screen formed of a plurality of wires, a rotatable frame, a series of soot-scrapers carried by the frame, each of said scrapers embracing 75 a wire of the screen, and means for operating said frame.

3. A spark arrester comprising a screen formed of a plurality of wires, a frame arranged externally of the screen, a series of 80 U-shaped scrapers secured to said frame and each extending around a wire of the screen, and a rack and pinion for imparting a relative movement to said frame and said screen.

4. The combination of a plurality of strands of wire arranged to form a spark arresting screen, a frame mounted for rotation relative to said screen, a plurality of scraping elements on said frame, one of 90 said elements for each strand of wire and embracing said strand, and means for moving said screen and frame relative to each other. •

5. The combination of a plurality of 95 strands of wire arranged to form a spark arresting cage, a frame rotatably mounted on the cage and disposed externally thereof,

a scraping element for each strand of wire secured to said frame, and means for rotating said frame.

6. The combination of a plurality of strands of wire arranged to form a spark arresting cage, a frame enveloping said cage and rotatably mounted thereon, a scraping member for each strand of wire projecting

from said frame and extending around said strand, and means for rotating said frame. 10

In testimony whereof I have hereunto set my hand.

JOHN GEORGE TORR.
